UNITED STATES PATENT OFFICE.

JOSEPH S. DUNCAN, OF CHICAGO, ILLINOIS, ASSIGNOR TO ADDRESSOGRAPH COMPANY, OF CHICAGO, ILLINOIS, A CORPORATION OF ILLINOIS.

PRINTING DEVICE.

1,026,246.

Specification of Letters Patent.

Patented May 14, 1912.

Application filed May 7, 1910. Serial No. 559,905.

To all whom it may concern:

Be it known that I, JOSEPH S. DUNCAN, a citizen of the United States, residing at Chicago, in the county of Cook and State of Illinois, have invented new and useful Improvements in Printing Devices, of which the following is a specification.

This invention relates to that class of printing devices which comprise a printing form and an information card and are adapted to be stored in accordance with a card index system or stacked in a pile.

One of the objects of the invention is to provide a printing device of simple and inexpensive construction in which the frame and the printing form are combined in one integral device, being made out of sheet metal with type characters stamped therein for the printing form, and formed into a frame to prevent contact with the face of the type characters when the devices are stored or stacked, and to strengthen and stiffen the device.

A further object of the invention is to provide the device with a card adapted to receive an impression from the whole or a part of the printing form, and with means for removably securing the card in place in the device.

For the purposes of convenience and economy it is desirable to make printing devices of this general character as small, light, simple, and cheaply as possible, and at the same time they should be sufficiently strong to keep their shape.

The invention has for its object to provide a printing device answering all of these requirements and for this purpose the card is preferably made narrow to receive, say, only two lines, whereas the printing form may contain more than two lines, and it may be mentioned now that the card may receive impressions from any two lines of type of the printing form or it may receive any other information.

In the accompanying drawings Figure 1 is a front view of a printing device embodying my invention. Fig. 2 is a bottom edge view. Fig. 3 is an enlarged transverse sectional view of the device. Fig. 4 is a back view of the device.

The drawings illustrate my invention in what I now regard as the simplest and most desirable form, the printing plate section 5 having five lines of type, although I do not

consider the number of lines a matter of material importance, and the card 6 having only two lines of printing. When a narrow card is used, as shown, the device can be made comparatively small and the cost of 60 production is correspondingly lessened.

The device is made out of a single sheet 7 of metal and it comprises the printing plate section 5 in which the type characters 5' are stamped or pressed by any suitable 65 means. The ends of the sheet are bent to form spacing flanges 8 at the back of the device and between these spacing flanges the upper and lower edges of the sheet are turned inwardly upon the front of the sheet 70 to provide strengthening and stiffening beads 9 and 10. Between the printing plate and the bead 9 a rib 11 is pressed upward on the front of the device from the back thereof and this rib extends parallel with the bead 75 9 and between the spacing flanges. The bead 9 is adapted to receive one edge of the card 6 and lips 12 are struck up from the rib 11 to receive the opposite edge of the card. A lip 13 is struck up from the sheet to receive one end of the card and the other end is adapted to engage a stop 14, also struck up from the sheet. An index tab 15 may be 80 cut and bent up to project from the beaded edge 9 of the device, in any desired position 85 between the spacing flanges, and this tab is adapted to have a type character pressed or stamped therein, or otherwise applied thereto.

My improved printing device is strengthened and stiffened longitudinally by the beads 9 and 10 and the rib 11 and transversely by the spacing flanges 8. I now prefer that the faces of the printing characters should lie in a plane below the beads 95 and rib, thus additionally protecting the type characters from injury, but for some purposes it will be sufficient to rely upon the spacing flanges for this protection and the faces of the type characters may lie in a 100 plane above the beads and rib. When the devices are stored on edge in a drawer or stacked in a pile one upon the other the spacing flanges will prevent contact of one device with the printing characters on the 105 next adjacent device, and this protection is increased when the beads and rib project beyond the faces of the printing characters, as shown.

For many purposes it will be sufficient if 110

- the card bears an impression of only a portion of the address appearing in the printing form, as shown in the drawings, but the card may be made of sufficient size to receive 5 an impression of the entire form and the device constructed to receive such a card. Instead of receiving an impression from the printing form of the device the card may bear any other desired information.
10. This device is so strengthened and stiffened that it can be made of comparatively thin and light metal whereby a greater number of the devices may be stored or stacked in a given space and this not only reduces 15 the cost of production but also provides for a material economy in the use of such printing devices.

What I claim and desire to secure by Letters Patent is:

20. 1. A printing device comprising a metal blank having opposite edges bent to form spacing flanges, and a rib stamped up from the blank, extending at substantially right angles to the spacing flanges throughout substantially the length of the space between the flanges, and disposed intermediate of the other edges of the blank and dividing the blank into a card-receiving space at one side of the rib, and a printing space at the other 30 side of the rib.
2. A printing device comprising a metal blank having opposite edges bent to form spacing flanges, the other opposite edges being bent to form stiffening beads, and the 35 metal of the blank being stamped from the back forwardly to form a continuous groove at the back of the blank and a continuous rib on the front of the blank, said rib lying between the stiffening beads and parallel 40 therewith and extending substantially throughout the length of the space between the spacing flanges and dividing the blank into a card receiving space between the rib and one of the beads, and a printing space 45 between the rib and the other bead.
3. A printing device comprising a metal blank having opposite edges bent to form spacing flanges, the other opposite edges being bent to form stiffening beads, a rib 50 stamped up from the blank in substantial parallelism with the beads and dividing the blank into a card-receiving space between the rib and one of the beads, and a printing device 55 between the rib and the other bead, the printing space having printing characters stamped therein.
4. A printing device made out of a single sheet of metal and comprising a printing plate section having printing characters 60 stamped up therefrom and on the front thereof, the ends of said sheet being bent to form spacing flanges, the edges of the sheet between the spacing flanges being bent to

form beads, and a rib stamped up from the sheet and extending between the spacing 65 flanges and parallel with and between the beads, said spacing flanges being at the back of the device and said beads and rib being at the front of the device.

5. A printing device made out of a single 70 sheet of metal and comprising a printing plate section having printing characters stamped up therefrom and on the front thereof, the ends of said sheet being bent to form spacing flanges at the back thereof, the 75 edges of the sheet between the spacing flanges being bent to form beads, and a rib stamped up from the sheet and extending between the spacing flanges and parallel with and between the beads, said beads and 80 rib being on the front of the device and projecting above the face of the printing characters.

6. A printing device made out of a single 85 sheet of metal and comprising a printing plate section having printing characters stamped up therefrom, the ends of such sheet being bent to form spacing flanges and the edges of the sheet between the spacing flanges being bent to form beads, a rib 90 stamped up from the sheet and extending between the spacing flanges and parallel with and between the beads, a card, one of said beads being adapted to receive an edge 95 of the card, and lips struck up from the rib to receive the other edge of the card.

7. A printing device comprising a metal blank having opposite edges bent to form spacing flanges, a rib struck up from the blank in substantial parallelism with the 100 other edges of the blank and extending throughout substantially the distance between the flanges, said rib dividing the blank into a card-receiving space at one side of the rib and a printing space at the other side 105 of the rib, said printing space having printing characters stamped therein.

8. A printing device made out of a single 110 sheet of metal and comprising a printing plate section having printing characters stamped up therefrom, spacing flanges at the ends of the plate, beads at the edges of the device between the spacing flanges, a rib 115 extending between the spacing flanges and parallel with and between the beads, a card located in the space between the rib and one of the beads, devices struck up from the rib and the sheet to engage the card and one of said beads being also adapted to engage the card to hold the card in place, and an index tab stamped out of the sheet and projecting outward from said bead.
